US00D525267S

(12) **United States Design Patent** (10) Patent No.: **US D525,267 S**
Canova et al. (45) Date of Patent: **** Jul. 18, 2006**

(54) **AIRFLOW CONVERGER**

(75) Inventors: **Carlos Augusto Canova**, São Paulo (BR); **Fábio Moreira**, São Paulo (BR)

(73) Assignee: **Sogefi Filtration do Brasil LTDA**, State of São Paulo (BR)

(**) Term: **14 Years**

(21) Appl. No.: **29/214,445**

(22) Filed: **Oct. 1, 2004**

(30) **Foreign Application Priority Data**

May 31, 2004 (BR) 6401809

(51) **LOC (8) Cl.** **15-01**

(52) **U.S. Cl.** **D15/5**

(58) **Field of Classification Search** ..... D15/1-9; 123/22, 26, 1 R, 41.56, 306; 98/61, 115.1; 261/71, 454, DIG. 84; 454/156, 158, 3, 11; D23/146-151, 365; 366/341; 138/37, 39, 138/45-46, DIG. 94; 55/252, 276, 385.3, 55/490, 43, 418, 492, 508, 506, 510, 434, 55/440, 365, 331, DIG. 18, DIG. 28, DIG. 36, 55/DIG. 31; 285/132.1
